CAN CHANGING MECHANISM FOR TEXTILE MACHINES

Odus C. Hinson, Cramerton, N. C., assignor, by mesne assignments, to The Terrell Machine Company, Charlotte, N. C., a corporation of North Carolina

Application April 5, 1945, Serial No. 586,651

11 Claims. (Cl. 19—159)

1

This invention has at its object the provision of novel and improved means for automatically transferring the delivery of sliver produced by a combing machine, card, drawing frame, or other textile machine, from a full can to an empty can when the first of such cans become filled to capacity.

In various textile machines which deliver their product in sliver form, it is common to provide in connection with the coiler mechanism which coils the sliver into cans at the delivery end of the machine, a stop motion device which stops the machine when the can into which the sliver is being coiled becomes filled to capacity. While the action of this stop motion prevents overflow and consequent disorder and damage of the sliver, it leaves the machine stopped and idle until the attendant shall note the condition, remove the full can and replace it by an empty can, and restart the machine by hand.

To prevent this loss of machine time and production, the invention provides self-acting means automatically stopping the machine after a predetermined measured length of sliver has been coiled into one can, transferring the delivery of sliver to an adjacent empty can, and again restarting the machine and the coiling mechanism to deliver the same measured quantity of sliver into the empty can. Thereby the production of the machine is interrupted only for the few seconds involved in shifting the delivery means from the full can to the empty can, with no dependence on the attention of the operator, who is thus given the full length of the prolonged period required to fill the empty can during which to remove the filled can and put an empty one in place in readiness for the next shift.

To these ends, the invention comprises in its preferred and complete form a plurality of rotated can-supports, and a coiling device shiftable from a position above a can located on one of such supports to a position above a can located on another of such supports, the shifting of such coiler mechanism being effected by power means actuated by devices which measure the length of sliver delivered, and which power means also interrupt the driving of the machine producing the sliver, the shifting means being contrived to restart such main drive at the completion of the shifting movement. Preferably also, the driving of the rotating can-supports is selectively shifted and confined to the one which holds the can then being filled.

Other objects of the invention, and the manner of their attainment are as set forth hereinafter.

2

An illustrative embodiment of the invention is shown in the accompanying drawings, in which Fig. 1 is a front elevation.

Fig. 2 is a side elevation.

Fig. 3 is a plan view.

Fig. 4 is a plan view of the driving means for the rotating can-supports.

Fig. 5 is a diagram of the electrical controls and connections used.

10 Fig. 6 shows the counter mechanism which calls the can change.

The invention is shown applied to the delivery end of a multiple head cotton combing machine, of which the uprights supporting the working

15 parts (not shown) of a single comber head are indicated at 1 as mounted on a longitudinal frame-member 3 supported on legs 5. At 7 is indicated the sliver table along which the slivers from the several heads are drawn in parallel re-

20 lation by drafting rolls located in the draw-box 9, the slivers being gathered into one as they leave the draw-box by a trumpet 11 through which the resulting single sliver is drawn by condensing rolls 13, all as heretofore.

25 In accordance with the invention, the single sliver emerging from rolls 13 travels upwardly and over a quadrant-shaped guide 15 fixed on the novel shifting coiler head 17 of the invention, passing over the top surface thereof, around a

30 cylindrical guide 18 in one working position of head 17, and down through a rimmed aperture 19 in the top of a housing 21 and between a pair of opposing calender rolls 23 fixed on shafts 25 mounted in bearings 27 within the housing, the

35 shafts being geared together by pinions 29 to turn in unison in opposite directions and one thereof being driven by bevel gears 31 from vertical shaft 33 within a hollow column or housing 35 suitably mounted on the end frame of the

40 coiling machine and constituting a support for the coiler head. The sliver is drawn downward by the rolls 23 and fed into the axially located upper end of the usual outwardly and downwardly inclined spout 37 integrally formed in the coiling member 39 rotatably mounted in its housing

45 41 and driven from a spur gear 43 fixed on vertical shaft 33 through an idler gear 45 engaging with teeth on the periphery of coiler member 39. The sliver emerging from the spout is thus laid in the usual coiled relation into one of the cans 47, positioned in slightly eccentric relation to the coiler member. A lip 49 of the housing 41 extends out over the can mouth, to hold down the coiled sliver when the can becomes filled beyond the level of its mouth. Housing 21 is hinged to hous-

ing 41 at 51, and is provided with a knob 53 whereby it can be lifted up and swung back in threading up.

To provide for automatically shifting the delivery from a full can to an empty can, the coiler head is mounted to swing horizontally about the axis of the column 35, by forming the top portion of such column with a tubular extension or hub 57 of reduced diameter, which hub fits easily within a corresponding sleeve 58 bolted by means of its flange 61 to the bottom of housing 41, so that the coiler head can swing about the axis of the column. To swing the coiler head, a rod 63 is fixed in a hub 65 forming a part of plate 61 of the head and also in a hub 67 in the end of one arm of a lever 69 mounted free on shaft 33 by means of its central hub 71 and an extended bushing 73 fixed therein. Rod 63 is connected at about midlength to a link 75 which has a hub 77 fitting around the rod and supported by a collar 79 fixed on the rod. The other end of this link is connected by a clevis 81 and pin 83 with an ear on a hub 85 rotatably mounted on a pin 87 fixed in the end of a crank arm 89 rotated a half turn, when can change is needed, in any appropriate manner, herein by fixing the crank arm on a jackshaft on which a worm gear 90 is fixed within a reduction gear box 91, such gear being driven by a worm 92 on the shaft 93 of a small electric motor 95.

The energizing of motor 95 is controlled by a yardage counter 97 of known or any preferred design which is driven by shaft 99 conventionally driving the lower calender rolls mounted in the sliver table 1 at the front of the pan which receives the combed web from each combing head. A familiar form of "hunting tooth" type of textile counter is herein used for the purpose, comprising a pair of intermeshing gears 180, 182, Fig. 6, one of which has one more tooth than the other, so that when driven by a pinion 184 on shaft 99 the two strikers 186 respectively fixed on the two gears will come together at the end of a long series of turns of shaft 99. This thrusts gear 182 away from gear 180 which latter is mounted on a fixed center, gear 182 being carried on a pivot 188 fixed in the forked end of a lever 190 swinging on fixed pivot 192 and having a screw 194 fixed in its other end the head of which engages the plunger 196 of switch 198 normally in "on" position. Actuation of switch 198 is momentary only, as the momentum of the parts carries strikers 186 past centers far enough so that pull spring 200 anchored at 202 swings lever 190 reversely and restores gears 180, 182 to full mesh. After the number of revolutions of this calender roll shaft corresponding to the predetermined yardage of sliver desired to be put into each can 47, counter 97 acts in described manner to interrupt the current supply to the main motor driving the comber and simultaneously closes a circuit supplying electric current to motor 95, which runs until crank 89 has been given a 180° angular movement, at which instant a switch in reduction gear box 91 actuated by the movement of the worm gear opens the circuit to can-change motor 95 and closes the circuit of the main motor, restarting the combing machine. The 180° movement imparted to crank 89 is transmitted through link 75 to move rod 63 bodily sideways, swinging the entire coiler head 17 through substantially 80° of angular movement about the axis of column 35, thus moving the coiler member 39 and its spout from over the filled can and into a position over the empty can to deliver its sliver into the empty can. In the

course of this shift, since the delivery of sliver from the spout is stopped at the moment, the sliver parts at a point between the spout and the top of the coiled mass extending up from the mouth of the filled can and pressing against the under side of housing 41.

As heretofore, the can being filled is rotated about an axis eccentric to that about which the delivery end of the spout 37 revolves, and for this purpose, a turn-table 100 is provided to support each can, having a raised flange 102 to receive the base of the can. To rotate these can-holders, a pinion 101 is fixed on the foot of vertical shaft 33, which pinion meshes with the larger gear 103, of a compound gear rotating on a pin 105 fixed in the end of a lever 107 swinging freely about shaft 33, so that the smaller gear 108 of the compound gear meshes with that one of the two large gears 109 respectively connected with a given turn-table 100 when the coiler head 17 is in delivery position over the can on such turn-table. A lost-motion connection comprising a radial arm 110 rigid with arm 69 and swinging between upstanding flanges 112 on lever 107 reduces the angular displacement of such lever to that needed to make the gear change. Thus, when the coiler head is shifted from over a filled can to a position over an empty can, the gear drive located in the turn-table platform 111 is shifted from the turn-table 100 holding the full can to the turn-table supporting the empty can, and the latter can is duly revolved while the coiler head delivers the sliver thereinto, the filled can remaining at rest. Gears 109 are respectively fixed on stub-shafts 113 rotatably mounted in suitable bearings in connection with platform 111 and forming the rotatable supporting and driving means for the turn-tables 100.

The drive for the coiler mechanism is taken from any going part of the machine to which the automatic can-changing device is applied. Herein the drive is obtained from the end of the half-lap shaft 114, Fig. 3, of the combing machine, by extending the jackshaft 115 driving the drawing rolls in draw box 9 so that it extends from within gear-box 10 into coiler column 35, where it imparts rotation to vertical shaft 33 by means of bevel gears 117. A third bevel gear 119 meshing with the one on shaft 33 is employed to transmit motion by way of an added jackshaft 121, Fig. 2, and intervening chain 123 and sprockets located within a guard 125 to the shaft 127 of lower calender roll 13.

The details of the electrical controls and connections employed to cause the device to work in the manner described are shown in Fig. 5. After the comber has run long enough to put the intended amount of sliver into the can being filled, the yardage counter 97 acts to close its circuit-maker momentarily, current from the 550-volt 3-phase line 131 passing through the closed manually operated cutout switch 133 and stepped down to 12 volts by transformer 135 energizes the coil of a magnetic switch 137 to close a second circuit energizing the motor 95 with 110-volt current obtained from the low side of transformer 139. Motor 95, as previously explained, shifts the coiler head 17 from over the full can to a position over the empty can, by means of worm 92 upon its shaft 93 engaging with worm gear 90 located within housing 91 and fixed on the shaft of crank 89. On this same shaft carrying the worm gear and crank 89 there is also fixed a contact disk 141 connected to ground and having a circular periphery provided with two diametrically opposite notches 143 cut deeply therein. A

contact-maker 145 to engage the full-diameter periphery of disk 141 is connected with that end of the coil of switch 137 that is connected with the yardage counter. Thus when yardage counter 97 momentarily completes the circuit through switch 137 to start motor 95, the contact-maker 145 makes contact with the rim of disk 141 as soon as the motor starts, thus holding switch 137 closed and the motor energized, in spite of the reopening of the circuit in yardage counter 97, until the worm gear 90 and disk 141 have completed a half-turn, whereupon the alternate notch 143 arrives opposite contact-maker 145, opening the circuit through switch 137 and thereby opening the motor circuit to stop the driving of crank 89 after 180° of travel.

In order to stop the combing machine while the shift of the coiler head is being accomplished, a main switch 147 is interposed in the leads carrying the 550-volt current to the main motor which drives the combing frame, this switch being spring-biased to remain normally open but mechanically connected with the armature of a solenoid 149 in a circuit fed by the 550-volt leads, so that when the solenoid is energized the main motor switch 147 will be closed, and when the solenoid is deenergized the main switch will again open automatically. Solenoid 149 is normally energized by a circuit comprising wire 159 from one of the leads 131 beyond the main motor switch 147, and wire 160 from another of the leads 131 before main motor switch 147, this circuit including the winding of the solenoid and a circuit closer 154 of commercial design forming no part of my invention (Cat. No. CR2960-SY-70R of General Electric Co.'s catalog GEA-606L, copyrighted 1943), having a contactor 158 normally making contact with the terminal of wire 160 to keep the solenoid energized and main switch 147 closed while the combing frame is running. When the coil of switch 137 is energized to close its contactor 153 to supply current to the coiler-shifting motor 95, a non-conducting mechanical linkage or interlock 151 between contactor 153 and the operating handle of circuit closer 154 opens contactor 158 thereof to break the circuit through the solenoid 149 and allow spring 161 to open the switch 147 to stop the main motor driving the combing frame. As soon as the rotation of contact plate 141 has again opened the circuit through magnetic switch 137 and allowed contactor 153 to open the circuit through motor 95, the mechanical linkage 151 acts on circuit closer 154 to restore contactor 158 to closed position in contact with the terminal of wire 160, and at the same time to make only momentary contact between such terminal and a second contactor 155 which is connected to a wire 156 attached to the same lead 131 as wire 159, but attached thereto at the other side of main motor switch 147. Current is thereby momentarily supplied by the contactor 155, located within circuit closer 154, to solenoid 149 to close main switch 147 and restart the combing machine, thereby reestablishing the holding circuit through wire 159 and the solenoid to keep main switch 147 closed. A second circuit closer 162 identical with 154 is provided in series multiple with the latter in wires 156, 160, for manual starting and stopping of the combing frame.

While I have illustrated and described a certain form in which the invention may be embodied, I am aware that many modifications may be made therein by any person skilled in the art,

without departing from the scope of the invention as expressed in the claims. Therefore, I do not wish to be limited to the particular form shown, or to the details of construction thereof, but what I do claim is:

1. Apparatus for delivering sliver into cans, comprising in combination a machine producing sliver, means coiling the sliver into a can, means stopping the driving of such machine upon delivery of a predetermined amount of sliver, means transferring the delivery of sliver from such can to an adjacent can, and means restarting the machine to produce more sliver after the transfer has been effected.
- 15 2. Apparatus for delivering sliver into cans comprising in combination a machine producing sliver, driving means therefor, means coiling the sliver into a can, means transferring the delivery of sliver from such can to an adjacent can, driving means for the transferring means, and devices effecting alternating and successive operation of the two driving means after each delivery of sliver for a predetermined period of the operation of the machine.
- 20 3. Apparatus for delivering sliver into cans comprising in combination a machine producing sliver, a coiler head having a revolving spout coiling the sliver into one of a plurality of cans, means supporting the coiler head for movement from a position in which it delivers the sliver into one of such cans to a position in which it delivers the sliver into another of such cans, and means stopping the production of sliver upon delivery of a predetermined amount of sliver, then effecting the said movement of the coiler head, and then restarting the machine.
- 25 4. Apparatus for delivering sliver into cans comprising in combination a machine producing sliver, can-holders each supporting a can with capacity for rotation about a separate fixed axis coinciding with the axis of such can, means delivering sliver into the several cans in succession, power driving means rotating the can-holders about the said axes and means successively putting said power driving means in driving connection solely with the can-holder supporting the can receiving the delivery of silver.
- 30 5. Apparatus for delivering sliver into cans comprising in combination a machine producing sliver, a shiftable coiler head having a revolving spout coiling the sliver into a can, can-holders each supporting a can with capacity for rotation, driving means for rotating the can-holders, and means shifting the coiler head from a position over one can to a position over another can and establishing driving connection with the particular can-holder supporting the latter can.
- 35 6. Apparatus for delivering sliver into cans comprising in combination a machine producing sliver, a shiftable coiler head having a revolving spout coiling the sliver into a can, can-holders each supporting a can with capacity for rotation, means driving the coiler head and one can-holder from the machine, means stopping the driving of the machine, the coiler head, and the can-holder upon completion of a predetermined period of operation, and means actuated by said stopping means shifting the coiler head to a position over another can, shifting the drive from the said can-holder to the can-holder supporting the last-mentioned can, and restarting the machine, coiler head, and can-holder drive.
- 40 7. Apparatus for delivering sliver into cans, comprising in combination a machine producing sliver, a coiler head having a revolving spout,

means supporting such head for swinging movement about a vertical axis, and power means independent of the actuation of the said machine swinging the coiler head about such axis.

8. Apparatus for delivering sliver into cans, comprising in combination a machine producing sliver, a coiler head having a revolving spout, means supporting such head for swinging movement about a vertical axis, a link connected to the head in eccentric relation to such axis, and power means reciprocating the link transversely of such axis and positively actuating the link in both directions of its movement.

9. Apparatus for delivering sliver into cans, comprising in combination a machine producing sliver, a coiler head driven thereby having a revolving spout, means supporting such head for swinging movement about a vertical axis, can-holders each supporting a can with capacity for rotation, means selectively driving the can-holders, and power means independent of the driving of the coiler and its revolving spout shifting the coiler head from over one can to a position over another can and also putting the holder of the latter can in driving connection with its driving means.

10. Apparatus for delivering sliver into cans, comprising in combination a machine producing sliver, means coiling the sliver into a can, means stopping the driving of such machine after each delivery of sliver throughout a predetermined length of operation of the machine, means transferring the delivery of sliver from such can to an adjacent can, and means restarting the machine to produce more sliver after the transfer has been effected.

11. Apparatus for delivering sliver into cans, comprising in combination a machine producing sliver, means coiling the sliver into a can, an electric motor for driving said machine, means stopping the driving of the machine upon completion of a predetermined extent of operation of such motor, means transferring the delivery of sliver from such can to an adjacent can, and means restarting the machine to produce more sliver after the transfer has been effected.
